UNITED STATES PATENT OFFICE.

CORNELL FLAGSTAD AND OSCAR A. FLAGSTAD, OF MINNEAPOLIS, MINNESOTA.

COLLAPSIBLE CRATE.

Application filed March 3, 1925. Serial No. 12,974.

This invention relates to folding or collapsible crates and the main object is to provide a simple, practical and efficient crate in which side and end sections are hingedly secured to a hollow base so as to be foldable thereinto, and in which a cover section has means whereby it may be detachably secured either to the vertical sections when the crate is set up, or to the base section when the crate is collapsed so as to lock all the parts in a closely nested condition. A further object is to provide a collapsible crate which is particularly adapted for use in shipping automobile radiators of the Ford type, although it will be understood that it may be also used for other purposes, if so desired. Further and more specific objects will be disclosed in the course of the following specification, reference being had to the accompanying drawings, wherein;

Figure 1 is a top or plan view of the crate, as set up.

Figure 2 is a side elevation of the crate shown in Figure 1.

Figure 3 is an end view of the crate.

Figure 4 is an enlarged detail perspective view of one of the base corner irons.

Figure 5 is an enlarged detail section on the line 5—5 in Figure 1.

Figure 6 is a detail view, similar to Figure 5, but showing the cover bolt in an unlocked position.

Figure 7 is an enlarged detail section on the line 7—7 in Figure 3.

Figure 8 is a sectional view on the line 8—8 in Figure 7.

Figure 9 is a section on the line 9—9 in Figure 7, with a slight modification.

Figure 10 is a detail perspective view of the interior of one of the base corners.

Figure 11 is a detail view, partly in section, showing one of the radiator spacing and bracing devices.

Figure 12 is an enlarged detail section on the line 12—12 in Figure 11.

Figure 13 is a view similar to Figure 12, but showing a different construction of bracing iron.

Figure 14 is an enlarged detail perspective view showing a modification of the device illustrated in Figure 13.

Figure 15 is a plan view of a cross member used as a spacing device, as will herein-after be described.

Referring to the drawings more specifically and by reference characters A designates a base having a bottom 16 and an up-standing rim 17—18—19—20. Side sections B and C and end sections D and E are hingedly secured to the inner side of the rim 17—20 so as to be foldable thereinto, when the crate is collapsed, and a detachable cover section F is so constructed that it may be secured either to the vertical sections, when the crate is set up, or to the base member, when the crate is collapsed. This construction is shown in a general way in our Patent No. 1,485,973, which issued on March 4, 1924, and also in our copending application Ser. No. 736,535, filed on September 8, 1924, for collapsible crate, but we have now incorporated new features and details of construction which will be fully set out and more particularly described in the appended claims.

Referring to Figures 1, 2, 3, 4, and 10, and especially to Figure 4 it will be seen that the adjoining ends of the members 17—20, or the corners of the base are reinforced and secured together by members G, of novel construction. Each of these members consists of an angle iron, the main flanges of which are perforated, as at 21, so that they may be secured by nails to the members 17—20. One flange 22 (Fig. 4) has an angular extension 23 which is bent under the base and up against the inner face of the other flange 24, with which it is secured by common nails. The upper end of the flange 22 has a somewhat similar angular extension 25, which extends over the upper edge of the base and then down between the base and the flange 24. The lower end of the extension 25 has a perforation 26 which coincides with but is smaller than a corresponding perforation 27 in the flange 24, so that when a nail is driven into the base its head will strike the extension 25 only, and will not touch the flange 24. The object of this is to allow the extension 25 to move slightly upward from the perforation 27 should the wood of the base expand or swell from moisture.

The opposite inner sides of the base are also provided with locking members H (Figs. 2 and 10) by means of which the cover F may be locked to the base when the crate is collapsed or knocked down. These members H each consist of an inverted substantially U-shaped piece the opposite legs of which are provided with perforated flanges 28 by which the member may be secured in place.

The side sections B and C each consists of horizontal slats 29, 30, and 31, an inclined slat 32, and vertical slats 33 and 34, the latter of which are hinged at their lower ends to the base. The vertical slats 33-34 are cut out or preferably divided so as to receive sheet metal channel members 35 having flanges 36 which are secured to the slats, so as to form pairs of vertical 10 inwardly disposed channels, for a purpose later to be described. The upper ends of the side sections B, C are provided with pocket forming members 37 (Figs. 1, 2, and 5) in which the cover locking bolts engage. 15 Such pockets may be incorporated in and formed by the corner locker irons, as shown at 38 in the modification shown in Figure 9.

The end sections D and E each consists of an upper horizontal slat 39, an inclined slat 40, and almost vertical end slats 41 and 42, the lower ends of which are hingedly secured as at 43 to the base members 17-18. The hinge preferably employed for this connection is shown in Figure 10, and one 25 or both of its butts are preferably provided with pressed out projections, as 44 or 45, whereby when the end section is raised to a vertical position there will be a yielding tendency to press it slightly inward, and 30 thus keep it in locking engagement with the adjacent side sections.

The upper corner locker irons are somewhat similar to those shown in our Patent #1,485,973, except for certain improvements thereover, which will now be set forth, reference being made especially to Figures 1, 2, 3, 7, 8, and 9.

The side sections B and C are provided, at their upper corners, with U-shaped locker irons 46, formed of sheet metal, and provided each with a transverse slot 47 for the reception of a substantially T-shaped head extension 48 of the co-operating locking member 49 on the adjacent end section corner. The slot 47 is provided with converging entrance edges 50 (Figs. 3 and 8) so that it will receive the neck 51-52 of the T-head 48 even though it does not enter or strike the slot strictly in the center thereof, and the inner end of the slot 47 is provided with notches or vertically opposed enlargements 53 for the neck portion 51 (which is wider than 52) so that when the crate is set up there will be a yielding tendency to keep the lock members 46 and 49 engaged, as there is almost always a slight tendency for either the end or side section to sag a little below the other. It will also be noted that the T-head 48 is provided at its ends with inwardly formed cam portions 54, which, when in locked positions (see Fig. 7) are just within or past the center of co-operating cams 55, which are pressed inwardly from the plate 46, with a result that there 60 will be a further or additional tendency to

retain the corner irons in an interlocked position, until manually released.

The cover section F, shown in Figs. 1, 2, 3 and particularly Figs. 5 and 6, consists of longitudinal slats 56, 57, 58, and 59, secured to transverse slats 60 and 61. The cover fits between the side and end sections, when the crate is set up, and thus holds them up in vertical position, and the cover slats 56, 57, and 59 extend beyond the outer transverse slats 61, so as to support itself on the end sections. The cover is secured in place upon the crate by a pair of rigid bolts or tongues 62, which are projected into the members 37, (or pockets 38), and, at the 70 opposite side of the cover, by a pair of manually retractable bolts 63, which operate between the slats 59-60 which in turn are preferably provided with wearing plates 64 and 65. The inner end of each bolt 63 is 75 provided with a vertical extension 66, which operates back and forth in a slot 67 in a plate 68, secured on the slat 60. A sheet metal latch member 69 is hinged to the plate 68, and is normally held down by a 80 spring 70. A portion 71 of the plate 69 is bent back (see Figs. 5 and 6) and is provided with a finger hole 72, whereby the member 69 may be lifted so that the bolt 63 may be retracted and released from the side 85 section. The member 69 is also provided, directly below the hole 72, with a pressed down concave 73, which, in addition to providing room for the operator's finger also serves to hold the member 69 up and the 90 bolt retracted, when the latter has been pulled back, as in Fig. 6. Thus, also, by a glance at the position of the finger member 69 the operator is able to readily determine whether or not the crate is locked 95 or unlocked. When locked (as in Fig. 5) the end of the finger piece is in direct and locking position against the bolt extension 66.

As previously stated the crate may be used for any purpose desired. As shown in the present instance, however, it is used for housing or inclosing four automobile radiators, and the radiators illustrated are of the Ford type, being designated as 74, 75, 76, and 77 in Figs. 1, 2, 11, 12 and 13. The radiators 74 and 75 are of the partly finished or completed form having laterally projecting flanges 78, while the radiators 76 and 77 are completed, having, in addition to the flanges 78, a pair of shield flanges 79, which extend parallel and adjacent to the flanges 78. Both types of radiators are shown as they are both frequently sent in the same crate.

In packing the crate the side and end sections are first set up, the cover being left off. The first radiator, 74, is placed, face down, upon the base, its flanges 78 extending into two opposite of the channels 35. A spacing bar 80 is then placed transversely across the 125

radiator, its ends fitting in the said channels, and serves as a support for one end of the radiator 75. Near or at the ends of the bar 80 are secured a pair of substantially W-shaped bracing irons 81, which fit snugly in the channels 35 and are so arranged that their central notches or recesses will straddle the flanges 78 and thus brace the entire radiator firmly in the crate. Adjacent to the members 81 the bar 80 is provided with notches 82 for the purpose of giving clearance to the water overflow pipe 83 (see Fig. 11) which lies adjacent to and forms a part of the standard Ford radiator. The member 81 at one end of the bar 80 has its lower outer corner cut away, as at the right in Fig. 11, so that when the bar is to be put in place or removed that end may be raised without binding in the channel member 35. And at the other or left end, the bar projects slightly beyond the brace, as in Figs. 11 and 14, and has its upper corner cut away, as shown, for the same reason.

After the bar 80 is secured in place a similar bar 85 (see Fig. 2) is secured in a reversed position in the other channels 35 so that it will, with the bar 80, space and support the second radiator 75, and so that its members 81 will receive the flanges 78 of that radiator and brace it in the same manner as the radiator 74 is braced, said radiator 75 being reversed so as to face upwardly.

The third radiator 76 is now ready to be inserted and braced, face down, but before this is done, a cross spacing member such as 86 (see Figs. 1 and 15) is placed upon the radiator 75 to prevent the two radiators 75 and 76 from meeting and bruising each other.

The third and fourth radiators are now ready to be packed and as here shown, are of the types having the shields 79 which extend with the flanges 78 into the opposite channels 35. Spacing bars such as 87 and 88 are interposed between these radiators, but as the flanges 79 do not permit the use of members 81, we provide a bracing member construction such as shown in Figs. 2, 13, 50 and 14. In Fig. 2, for instance, the member 89 projects with a tapered end 90 down between the flange 78 and the channel, while a shoulder 91 is formed in the member to rest upon the upper edge of the flange. In 55 the modification shown in Fig. 14 the member 92 is quite similar to 89 except that it is further provided with a punched out abutment 93 which serves to stop against the outer edge of the radiator and prevent it 60 from moving laterally between the sides of the crate.

It is understood that various modifications may be made in the general design and structural details of the invention as herein 65 illustrated, and described, providing, how-

ever, that such modifications come within the spirit and scope of the appended claims.

Having now, therefore, fully shown and described our invention what we claim to be new and desire to protect by Letters Patent 70 is:—

1. A collapsible crate for radiators and the like, comprising a base, collapsible side and end sections and a removable cover, said side sections having oppositely disposed 75 vertically arranged channels adapted to slidably receive parts of the radiators, spacing members interposed between said radiators, and means at the ends of the members for engaging said radiator parts and rigidly securing them in the channels.

2. A crate for radiators and the like, opposite sides of the crate having inwardly disposed vertical channels, a spacing bar for each radiator, the same having its ends extending into opposite of the channels, and means at the ends of said bar for engaging opposite sides of the radiator to brace the same rigidly within the crate.

3. A crate for radiators and the like, opposite sides of the crate having inwardly disposed pairs of vertical channels, one pair near each end of the crate, a pair of spacing bars arranged between each pair of radiators and each extending with its ends 95 into one pair of said channels.

4. A crate for radiators and the like, opposite sides of the crate having inwardly disposed pairs of vertical channels, one pair 100 near each end of the crate, a pair of spacing bars arranged between each pair of radiators and each extending with its ends into one pair of said channels, and means on said bars for engaging said radiators to rigidly brace them within the crate.

5. A crate for radiators and the like, opposite sides of the crate having inwardly disposed pairs of vertical channels, one pair near each end of the crate, a pair of spacing bars arranged between each pair of 110 radiators and each extending with its ends into one pair of said channels, and means on said bars for engaging said radiators to rigidly brace them within the crate, the means on one bar engaging one radiator and 115 the means on the other bar engaging the other radiator.

6. A crate for radiators and the like, opposite sides of the crate having inwardly disposed vertical channels, a spacing bar 120 for each radiator, the same having its ends extending into opposite of said channels, and means at the ends of said bar for engaging opposite sides of the radiator to brace the same rigidly within the crate said means 125 consisting of brackets adapted to be slidably received in said channels.

7. A crate for radiators and the like, opposite sides of the crate having inwardly disposed vertical channels, a spacing bar for 130

each radiator, the same having its ends extending into opposite of said channels, and means at the ends of said bar for engaging opposite sides of the radiator to brace the same rigidly within the crate, said means consisting of angularly projecting brackets having tapered portions arranged to be interposed between a part of the channel and a part of the radiator.

10. 8. A crate for radiators and the like, opposite sides of the crate having inwardly disposed vertical channels, a spacing bar for each radiator, the same having its ends extending into opposite of said channels, and

15 means at the ends of said bar for engaging opposite sides of the radiator to brace the same rigidly within the crate, each of said spacing bars having a notch therein, as and for the purpose set forth.

20. 9. The combination with a crate having opposite inwardly disposed channels adapted to receive flanges of radiators and the like

placed in the crate, of bars arranged between such radiators or the like to space the same and extending with their ends into 25 said channels, of brackets at the ends of said bars, said brackets each having a tapered extension adapted to project between the channel and said flange.

10. A shipping box having foldable sides 30 provided with vertical guideways arranged to guide and hold projecting lugs of devices such as radiators, and spacing bars arranged to be placed between radiators and the like with their ends guided and held by 35 said guideways, said spacing bars near their ends having projecting wedge lugs engageable with the projecting lugs of said radiators or the like to crowd the same against opposite sides of respective guideways. 40

In testimony whereof we affix our signatures.

CORNELL FLAGSTAD.
OSCAR A. FLAGSTAD.
